(57) **CLAIM**

The ornamental design for an effortless duvet cover, as shown and described.

DESCRIPTION

FIG. 1 is a front perspective view of another embodiment of the effortless duvet cover showing our design;

FIG. 2 is a front view thereof;

FIG. 3 is a rear view thereof;

FIG. 4 is a side view thereof;

FIG. 5 is a side view thereof, opposite that shown in FIG. 4;

FIG. 6 is a top view thereof;

FIG. 7 is a bottom view thereof;

FIG. 8 is an effortless duvet cover in an open configuration with a top end pocket and a bottom or foot end pocket shown in broken lines; and,

FIG. 9 is a partial enlarged view of FIG. 1 that is included to more clearly depict the design from the right-side perspective view of FIG. 1.

(Continued)

The broken lines shown in the drawing views are included for the purpose of illustrating portions of the effortless duvet cover that form no part of the claimed design.

1 Claim, 7 Drawing Sheets
